UNITED STATES PATENT OFFICE

94,855

DESIGN FOR A CASING FOR A CUTTING INSTRUMENT OR THE LIKE

Elmer P. Sacrey, Syracuse, N. Y., assignor to
Syracuse ToolElectric Mfg. Corp., Syracuse, N. Y.,
a corporation of New York

Application May 15, 1934, Serial No. 51,791

Term of patent 7 years

To all whom it may concern:

Be it known that I, Elmer P. Sacrey, a citizen of the United States, residing at Syracuse, in the county of Onondaga and State of New York, and having my post-office address at 2011 South State Street, Syracuse, New York, have invented a new, original, and ornamental Design for a Casing for a Cutting Instrument or the like, of which the following is a specification, reference being had to the accompanying drawing forming part thereof. In the drawing,

Figure 1 is a plan view of this instrument.

Figure 2 is a side elevation thereof.

Figure 3 is an end view looking to the right in Figure 2.

I claim:

The ornamental design for a casing for a cutting instrument or the like substantially as shown and described.

In testimony whereof, I have hereunto signed my name, at Syracuse, in the county of Onondaga, and State of New York, this 11th day of May, 1934.

ELMER P. SACREY.

CERTIFICATE OF CORRECTION.

Design No. 94,855.

March 12, 1935.

ELMER P. SACREY.

It is hereby certified that error appears in the printed specification of the above numbered patent requiring correction as follows: Second column, after line 3, insert the following paragraph:

The predominating features of the design are the ellipsoidal body and the ellipsoidal head as well as the general appearance resulting from the union of the body and the head and their angular relative disposition in the manner shown.

And that the said Letters Patent should be read with this correction therein that the same may conform to the record of the case in the Patent Office.

Signed and sealed this 25th day of June, A. D. 1935.

Bryan M. Battey
